R. H. REITER

PISTON RING

Filed Dec. 2, 1920

FIG 1

12' FIG 2

Fig. 3

FIG. 4

Ralph H. Reiter Inventor

By F. E. Shannon Attorney

UNITED STATES PATENT OFFICE.

RALPH H. REITER, OF AKRON, OHIO.

PISTON RING.

Application filed December 2, 1920. Serial No. 427,794.

To all whom it may concern:

Be it known that I, RALPH H. REITER, a citizen of the United States, residing at Akron, in the county of Summit and State 5 of Ohio, have invented new and useful Improvements in Piston Rings, of which the following is a specification.

This invention relates to improvements in metallic packing rings and has particular 10 reference to a new and improved piston ring which may be used to advantage in explosive engines, on the pistons of pumps and, in general, on devices wherein a tight joint is necessary between a piston and a cylinder 15 wall.

It is well known that a piston fitted with new rings will provide a tight joint between the piston and the cylinder wall only after a period of use and that an engine must be 20 operated for some time with a considerable loss of compression before the rings are properly seated.

The main object of this invention is to provide a quick seating packing ring which 25 in use will quickly adapt itself to slight irregularities in a cylinder wall.

A further object is to provide a strong durable one-piece ring of simple construction which will effectually seal the joint between the piston and the cylinder wall. 30

The above and other objects are accomplished by the novel construction, herein-after described and illustrated in the accompanying drawings in which I have 35 shown a preferred embodiment of the invention, it being understood that the invention is capable of various adaptations and that changes and modifications may be resorted to which come within the scope of the 40 claim hereunto appended.

In the drawings in which similar numerals of reference are employed to designate corresponding parts throughout the several views,

45 Figure 1 is a perspective view of a piston ring constructed in accordance with this invention.

Figure 2 is a side view of same.

Figure 3 is an enlarged perspective view 50 of a portion of the ring shown in Figures 1 and 2.

Figure 4 is a transverse sectional view taken as indicated by the lines 4—4 of Figure 1.

Referring now to the drawings in detail, 55 the numeral 5 is used to denote the ring body which, in the main, is of the usual rectangular cross section. The peripheral face of the ring is provided, adjacent each edge, with a plurality of longitudinally directed, circumferentially extending ridges 7, which are of triangle cross section, disposed thereon base to base, so as to project outwardly from the central peripheral portions 6 of the ring. 60 The ridges 7 are preferably minute, projecting only about .002 of an inch beyond the central circumferential surface 6 of the ring body 5; the size of said ridges 7 being greatly exaggerated in the drawing, to more 65 clearly illustrate the invention. The ring 5 is cut as at 8 and is provided with abutting ends 9 and 10. The cut 8 extends vertically upward from the bottom of the ring body 5 to a point approximately central of the 70 smooth surface 6, from which point it extends at a right angle to the said vertical cut and parallel to the ridges 7. The cut is then directed at an acute angle to the last mentioned cut terminating at a point in alignment with the lower or vertical part of the 75 cut 8. This provides an oblique cut 12 through the upper part of the ring body 5 and a step cut 11 through the lower part of the ring body 5, thus providing a reliable 80 and effective juncture between the ends 12 and 13.

In use, a ring constructed in accordance 85 with this invention is placed on a piston in the ordinary manner and the piston is operated in the usual way in a cylinder. Inasmuch as each rib 7 presents a narrow surface to the cylinder wall, the said ridges quickly wear down in conformity with the 90 contour of the cylinder and the engine need be operated only a short period of time until the ring has adapted itself to every 95 irregularity that may exist in the cylinder walls.

While I have shown and described a ring 100 provided with a wearing face provided with a ridged area adjacent each edge thereof, it is to be understood that a ring may be constructed with any desired number of projecting ridged areas.

Having thus described my invention what 105 I claim as new and desire to secure by Letters Patent is;

In a piston ring, a ring body provided on

its peripheral face adjacent each edge thereof with a set of parallel outwardly projecting, longitudinally directed circumferentially extending ridges of triangular cross section, disposed thereon base to base, said sets of ridges spaced apart to provide a centrally disposed circumferentially extending smooth, substantially cylindrical area of the

same diameter as the base of said ridges, the outer face of each outermost ridge meeting the axial face of the ring and disposed at an angle thereto. 10

In testimony whereof I have hereunto set my hand.

RALPH H. REITER.
